(57) CLAIM

The ornamental design for a jewelry arrangement, as shown and described.

DESCRIPTION

FIG. 1 is a perspective view of a jewelry arrangement, showing my new design; and,

FIG. 2 is a front view thereof.

The broken lines are provided for illustrative purposes only, and form no part of the claimed design. The claimed design is directed to one or more edges of the jewelry arrangement, and not to any hole or interior surface thereof.
